UNITED STATES PATENT OFFICE

2,618,220

TYPE HOLDING APPARATUS

Peter J. Hahn, Sr., Chicago, Ill., assignor to Peter J. Hahn & Sons Company, Chicago, Ill.

Application December 21, 1948, Serial No. 66,460

2 Claims. (Cl. 101--368)

1

This invention relates to a new and improved type holding apparatus for use with stamping machines.

Foil stamping machines are those machines in which a stamping head employs type in combination with heat to cause foil, such as gold foil, to be imprinted on various objects according to the type held in the stamping head. Such a stamping head is shown in my co-pending application entitled "Foil Feeding Device For Stamping Machines," and having Serial No. 66,459 and filed December 21, 1948.

It is, therefore, a principal object of this invention to provide a type holding means for foil stamping machine.

An important object of this invention is the provision of type holding means for foil imprinting machines in which the type is securely held during the stamping or imprinting operation.

Another important object of this invention is to supply type holding means for a foil stamping machine having plural spring means for resisting lateral as well as vertical movement with respect to the stamping machine during the entire operation of the imprinting process.

A further object of this invention is to provide a type holding stick or the like having integral spring means in a T-head for the purpose of exerting lateral force against a cooperative T-slot in the stamping head, thus maintaining the type stick in fixed position with respect to the stamping head.

Another and further important object of this invention is to provide a stamping head having a type receiving socket and a leaf spring disposed in a channel extending laterally across the top thereof in which the end portions are disposed within the channel and the central portion extends downwardly within the socket, whereupon a type stick inserted in the socket may easily pass over the ends of the spring within the channel and when centered in the socket is yieldably held by the downwardly extending central portion of the spring.

A further important object of this invention is the provision of a stamping head for foil imprinting machines in which a type-holding stick may be inserted from only one end thereof, and the type stick is equipped with means associated therewith to permit either end thereof to be inserted into the single end of the stamping head and having cooperative means on the stamping head for engaging means on the type stick for centering the type stick within the stamping head.

2

Another and still further important object of this invention is to provide spring held spacer means for employment of various sizes of type within a single type stick holder.

Other and further important objects of this invention will become apparent from the disclosures in the following specification and accompanying drawing.

In the drawing:

Figure 1 is a perspective view showing the stamping head of this invention.

Figure 2 is a perspective view showing the type stick holder.

Figure 3 shows the type stick and stamping head of Figures 1 and 2 in cooperative engagement.

Figure 4 is a bottom plan view of the stamping head as shown in Figure 1.

Figure 5 is a sectional view taken on the line 5—5 of Figure 4.

Figure 6 is an end view of the stamping head.

Figure 7 is a partial perspective view of the type stick holder taken from the opposite side from that of Figure 2.

Figure 8 is a bottom plan view of the type stick holder of Figures 2 and 7.

Figure 9 is a perspective view detail of the spacer employed within the type stick holder.

As shown in the drawings:

The reference numeral 10 indicates generally an inverted U-shaped channel member which is adapted to form part of a stamping head for use on a foil imprinting machine. The inverted channel includes a cross top member 11, downwardly extending side members 12 and 13, and flanges 14 and 15 in the form of dovetails adjacent the top 11 for easy sliding insertion within the reciprocating head fixture of a foil imprinting machine as shown in my co-pending application mentioned above. The inverted U-shaped member forms a laterally extending channel or socket 16, within which a type holder may be easily slid. The U-shaped member 10 includes T-head slot portions 17 and 18 adjacent the underside of the top 11 and extending inwardly within the sides 12 and 13. The function of the T-head slot is to receive a T-head on a type holding stick to prevent vertical displacement of the type holder when it is in position within the U-shaped channel member 10.

A narrow, shallow channel or groove 19 is provided within the channel 16 along the top thereof within the top side 11 and centrally between the sides 12 and 13. The channel 19 is adapted to hold a leaf spring 20. An end 21 of the spring

is completely disposed within the channel 19 and fastened therein by means of a screw or the like 22. The middle portion of the leaf spring 20 designated by the numeral 23 is bellied or curved downwardly as best shown in Figures 1 and 5 and thereupon the opposite end 24 is turned upwardly and lies within the channel 19 as does the holding end 21. The downwardly extending central portion 23 of the leaf spring 20 is therefore located in the plane of the T slots 17 and 18 and upon sliding passage of the type holder within the inverted U-shaped channel member 10, the spring 20 has its central portion 23 compressed and thus the type holder is firmly held within the channel 16 by reason of the spring 20 exerting a downward force upon the type holder.

Figure 2 shows the type stick holder adapted to be inserted within the channel 10 shown in Figure 1. The holder of Figure 2 is substantially L-shaped, having a cross head 25 and a back wall 26. End walls 27 and 28 complete the structure for the type holder. The top 25 of the type holder or type stick as it is commonly called in the industry, is of a thickness equal to the T head slots 17 and 18 in the inverted U-shaped channel 10. The top 25 has laterally projecting side portions 29 and 30 for cooperative engagement with the slots 17 and 18 in the channel 10. The top 25 of the type stick thus constitutes a T head which slides into the T slots in the channel and holds the type stick against relative vertical movement between the type stick and holder 10. The top 25 is relatively flat, and upon insertion of the type stick within the channel 10, the spring 20 is compressed, thus holding the type stick in any position desired.

As best shown in Figures 2 and 8, the laterally extending edge or lip 29 is provided with an integral spring 31 which is formed by slitting the lip 29 at 32 and thereupon forming the central portion of the strip 31 convexly outwardly to constitute a laterally extending spring 31. Thus when the type holder is inserted into the holding head 10 it is held in two directions by means of dual springs. The first spring means shown at 20 is adapted to urge the type holder in a downward or vertical direction, and the second spring means is that shown at 31 which urges the type stick transversely within the type stick holder 10, thus insuring that regardless of looseness of fit of the lips 29 and 30 within the cooperative slots 17 and 18 the type stick will be firmly held within the holder, thus enabling clear impressions to be made by this imprinting machine.

The underside or bottom of the back wall 26 is calibrated in increments of type spacing as shown at 33. The type, whether it be a name and address or other symbols is placed within the L-shaped holder against the back wall and up against the top 25. When the type is inserted within the holder the holder is turned upside down so that the type maintains its position after placement. When the type row is completed a hand screw 34 is turned up against the end of the type by means of rotating a knurled or otherwise milled handle 35, thus pressing the type against the far end wall 28. As shown in Figures 2, 3 and 8, the hand screw 34 threadedly engages the end wall 27 at 36.

Styles of type vary considerably in size and although one style of type may take up the entire space between the back wall 26 and the depth of the holder as indicated by the width of the end walls 27 and 28, certain types are of smaller sizes

and thus of necessity a lateral spacing member is provided as shown at 37. This spacer member is shown in detail in Figure 9 wherein the member 37 is shown slotted at 38, forming an end finger member 39. This finger constitutes an integral spring for the spacer member 37. When the member 37 is inserted in the type holder as shown in Figure 8, the spring 39 causes an endwise force to be exerted on the end wall 27, whereupon the lateral spacing member is firmly and rigidly held within the type holder. The spacer 37 insures that the hand screw 34 will exert a pressure centrally of a row of small type.

Figure 3 best shows the assembly of the type stick within the holder. In order that the relatively long type stick may be conveniently centered within the type stick holder, the lips 29 and 30 are provided with opposite and diagonally disposed ledges or notched cutoffs as shown at 40 and 41 in Figures 2 and 7 respectively. As shown in Figure 6, a stop member 42 is fastened by means of rivets or bolts or the like 43, over the far end of the T slot 18. Thus as the type stick is slid into the holder, the ledge 40 strikes the stop 42, causing an automatic centering of the type stick within the holder. The ledges 40 and 41 are spaced an equal distance from the end walls 28 and 27 respectively, and thus permit an extension of the type stick beyond the end of the inverted U-shaped channel that amount which it does extend beyond the ledges 40 and 41. If it is desired to make an impression of the type within the holder in reverse direction, the type stick is then turned around and inserted into the same end of the channel and in that event the ledge 41 strikes the stop 42 and also centers the type stick within the holder head 10.

In the operation of this device the inverted U-shaped head 10 is fastened to a stamping head preferably by means of sliding the dovetail extension members 14 and 15 into cooperative socket dovetail slots in the stamping head of a stamping machine. Type of the desired size and in desired order is arranged in the type stick and the hand screw 34 tightened against the end of the row of type by means of rotating the handle 35. The type stick is then inverted and the T head 25 inserted into the T slots 17 and 18 of the head 10. The springs 20 and 31 hold the type stick in the channel 10 and with sufficient relative rigidity to permit impressions to be made without fear of shifting of the type stick within the stamping head.

It is believed that herein is provided a type holder for stamping machines which is simple in construction and yet performs all of its required functions. It is further believed that the spring mounted in the depressed channel of the inverted U-shaped channel member performs a very desirable function of maintaining the type stick holder free of relative vertical movement. This taken in combination with the spring 31 which is formed integrally with the T head of the type stick to exert a side pressure forms a very unique type holder for stamping machines.

Numerous details of construction may be varied throughout a wide range without departing from the principles disclosed herein and I therefore do not propose limiting the patent granted hereon otherwise than as necessitated by the appended claims.

What is claimed is:

1. In a stamping machine having a T-slotted type stick holder with an inverted U-shaped channel and a cooperative T-head type stick com-

prising spring means to maintain the T-head type stick free of relative movement with respect to the T-slotted type stick holder, said spring means including an integral spring formed on one side of said T-head type stick, said spring defined by a slit in the T-head type stick head and the spring curved convexly outwardly at the middle of the slit, whereby when the T-head type stick is inserted in the T-slotted type stick holder the integral spring causes a lateral force to be exerted within the T-slotted type stick holder.

2. In a stamping machine having a T-slotted type stick holder with an inverted U-shaped channel and a cooperative T-head type stick comprising means for longitudinally centering said T-head type stick in said T-slotted type stick holder, said means including shoulders on diagonally opposite corners of the T-head on the T-head type stick and a stop at one end and one side of the T-slot in the T-slotted type stick holder, whereby insertion of the T-head type stick is limited regardless of which end of the T-head type stick is inserted first, and whereupon centering of the T-head type stick is accomplished by one of the shoulders engaging the stop.
